DESIGN FOR A SHOULDER STRAP HOLDER

Frances Alberts, Brooklyn, N. Y.

Application December 19, 1940, Serial No. 97,463

Term of patent 7 years

To all whom it may concern:

Be it known that I, Frances Alberts, a citizen of the United States and resident of Brooklyn, New York, in the county of Kings and State of New York, have invented a new, original, and ornamental Design for a Shoulder Strap Holder, of which the following is a specification, reference being had to the accompanying drawing, forming a part thereof.

Fig. 1 is a top plan view of a shoulder strap holder with a portion thereof folded over, showing my new design.

Fig. 2 is a bottom plan view of the shoulder strap holder shown in Fig. 1.

Fig. 3 is an edge elevational view of Fig. 2.

I claim:

The ornamental design for a shoulder strap holder, as shown.

FRANCES ALBERTS.
